UNITED STATES PATENT OFFICE.

WILLIAM ROSE, OF GAINSBOROUGH, ENGLAND, ASSIGNOR TO ROSE BROTHERS (GAINSBOROUGH) LIMITED, OF GAINSBOROUGH, ENGLAND.

BAG-MACHINE.

1,354,339.

Specification of Letters Patent. Patented Sept. 28, 1920.

Application filed February 12, 1920. Serial No. 358,242.

To all whom it may concern:

Be it known that I, WILLIAM ROSE, a subject of the King of Great Britain, residing at Albion Works, Gainsborough, in 5 the county of Lincoln, England, have invented new and useful Improvements in Bag-Machines, of which the following is a specification.

This invention relates to apparatus for 10 making paper and like bags, or containers, of the kind in which a number of mandrels, or formers, upon which the bags, or containers, are made, are radially arranged on an intermittently rotatable sleeve, or shaft, 15 each mandrel, or former, being provided with a presser-foot, or bar, and means whereby, it is first caused to exert pressure upon the longitudinal seam of a bag, or container, on the mandrel, or former, and then to release 20 the pressure, and this invention has for its object to provide improved means for operating the presser-foot, or bar, which means will readily indicate whether, or not, the required pressure is being exerted, and which 25 will also maintain the pressure for a predetermined time.

We will describe our invention with reference to the accompanying drawing which 30 illustrates means in accordance therewith for operating the presser-foot, or bar, Figures 1 and 2 showing, in elevations at right angles to each other, the position of the parts when the presser-foot, or bar, is exerting pressure; Fig. 3 is a similar view to 35 Fig. 2, but showing the position of the parts when pressure is released. Figs. 4 and 5 are perspective views of details hereinafter referred to.

The sleeve, or shaft, on which the mandrels, or formers, are radially carried may 40 be mounted in a vertical, horizontal, or angular, position, but we will assume that it is mounted vertically, as shown in the accompanying drawing, so that the mandrels, or formers, rotate intermittently in a horizontal plane.

Each of a number of mandrels, or formers, 45 1, is rigidly carried on or formed in one with an arm 2, on a sleeve 3, which is, by 50 any known, or suitable, means, caused to be intermittently partially rotated on a shaft 4. To a bracket 5, or to an extension of the arm 2, is pivotally connected, by a link 6, the presser-foot, or bar 7. The application and 55 release of pressure by the said foot, or bar,

7, is effected by a vertically movable block, or die, 13, which is connected to the link 6, through a yieldable toggle-lever device, consisting of a lever 8, pivotally mounted on the bracket 5 and connected at one end 14, to the said block, or die; a bell-crank lever 9, pivotally mounted on a pin 10, at the free end of the said lever 8, and links 12, each of which has one of its ends connected to the end 11, of the lever 9, and its other end connected to the link 6. The lever 8, and the bell-crank lever 9, are provided with lugs, or the equivalent, 15 and 16, which are caused to abut (by the action of a spring 17, interposed between a projection 18, on the bell-crank lever 9, and an arm 19, on the lever 8) when the parts are in the position in which the pressure is released as shown in Fig. 3 of the accompanying drawing, but which separate (in opposition to the action of the said spring 17) when pressure is exerted, as shown in Fig. 2 of the accompanying drawing, so that by the position of the said lugs 15 and 16 relatively one to the other it can be readily observed whether, or not, the desired pressure is being exerted.

The block, or die, 13 is moved vertically, at the required times, to actuate the aforesaid toggle-lever device, by a reciprocating sleeve 20, (shown separately in Fig. 4 of the accompanying drawing) slidably mounted on the shaft 4, the said sleeve having a pair of outstanding jaws 21 and 21^a, between which, when the said sleeve is in its lowest position, the block, or die, 13, is, at the proper time, carried by the intermittent rotative movement of the sleeve 3, so that upon the ascent of the said sleeve 20, it will carry the said block, or die, upward with it, thereby operating the toggle-lever device which then acts to release the pressure and to raise the presser-foot, or bar, 7, from the mandrel, or former, 1, to the position shown in Fig. 3 of the accompanying drawing. The block, or die, 13, and the presser-foot, or bar, 7, are maintained in the raised position for a sufficient time to permit of the removal of the completed bag, or container, from the mandrel, or former, 1, and the wrapping, or folding, thereon of further material for making another bag, or container, after which the sleeve 20 and the block, or die, 13 descend and cause the toggle-lever device to press the presser-foot, or bar, 7, onto the longitudinal seam of the bag, or container,

on the mandrel, or former, 1, as shown in Fig. 2 of the accompanying drawing. During the downward movement of the block, or die, 13, the hereinbefore mentioned lugs, 15 and 16, remain in contact until downward movement of the presser-foot, or bar, 7, is arrested by its engagement with the bag, or container, on the mandrel, or former, 1, whereupon the bell-crank lever 9, is then caused, by the links 12, to turn on the pin 10, so that the lug 15, on the said bell-crank lever, is moved away from the lug 16, on the lever 8.

The construction and arrangement of the lever 8, bell-crank lever 9, and links 12, are such as to constitute an efficient yieldable toggle-lever device and the effect of the co-acting operation of the several members thereof is such that when the sleeve 20 has reached the limit of its downward movement, the end 11, of the bell-crank 9, has been forced, by the links 12, to approach the fulcrum of the lever 8, and, consequently the lug 15, on the said bell-crank lever, has been moved out of contact with the lug 16, on the lever 8, as before mentioned. By observing the relative positions of the lugs 15 and 16 it can be readily ascertained whether, or not, the presser-foot, or bar, 7, is properly bearing upon the longitudinal seam of the bag, or container.

The block, or die, 13, may be held in its lowered position so that the pressure is maintained on the bag, or container, while the sleeve is making a complete rotation, or a predetermined number of intermittent partial rotations, and this may be effected by a stationary piece 39, (shown separately in Fig. 5 of the accompanying drawing) having horizontal guides, or flanges, 41 and 41^a, with a gap 42 therein through which the jaws 21 and 21^a on the sleeve 20 pass when ascending and descending. The guides, or flanges, 41 and 41^a are so arranged that they are in alinement with the jaws 21 and 21^a when the sleeve 20 is in its lowest position, so that, upon a movement of partial rotation of the sleeve 3, the block, or die, 13, between the said jaws 21 and 21^a, passes therefrom to between the guides, or flanges, 41 and 41^a and is thereby retained in its lowered position so that the pressure on the longitudinal seam of the bag is maintained until, by further rotation of the sleeve 3, the block, or die, 13, is returned to between the jaws 21 and 21^a which then ascend through the gap 42 in the guides, or flanges, and effect the release of the pressure as aforesaid. Side-plates 43 and 43^a may be provided on the guide, or flange, 41, to prevent rotative movement of the sleeve 20 when in its raised position, and an annular recess 44 may be formed in the stationary piece 39 to receive the lower portion of the sleeve 20.

Any known, or suitable means, may be employed for effecting the reciprocation of the sleeve 20; it is shown, by way of example, in the accompanying drawing as being effected as follows:—Secured to the shaft 4, by a pin 26, is a boss 25, having pins 30, upon which is rotatably mounted an element consisting of an arm 28 carrying an antifriction roller 29, and arms 24 and 24^a connected by a bridge-piece 27. The free ends of the arms 24 and 24^a are pivotally connected, by links 23 and 23^a, pivotally mounted on pins 22 and 22^a, respectively, secured to the sleeve 20. The antifriction roller 29 engages with a cam 34 secured to a shaft 33 rotatably mounted in a bearing 32 formed in one with the boss 25. The weight of the sleeve 20 and the parts carried thereon tend to maintain the antifriction roller in engagement with the cam 34 and this tendency may be augmented by a tension spring 36 having one end connected to a pin 38, on the arm 24, and the other end connected to a pin 37, on the end of an arm 35, formed in one with the boss 25. The shaft 33 may be provided with a collar 46 to prevent longitudinal movement of the said shaft in the bearing 32. Rotary motion may be transmitted to the shaft 33 by any suitable means.

In the example of apparatus illustrated in the accompanying drawing each of the four mandrels, or formers, is provided with a toggle-lever device and an actuating die, or block, 13, and therefore the sleeve 3 will make four intermittent partial rotations in making a complete rotation, so that, at the end of each intermittent rotation, each block, or die, will be successively brought into position to be raised and lowered by the jaws 21 and 21^a on the sleeve 20.

It is to be understood that the invention is not limited to the precise construction and arrangement of the parts hereinbefore described and shown in the accompanying drawing, nor to the number of mandrels, or formers, employed, as modifications may be made without departing from the nature of the invention; for example, eight mandrels, or formers, may be employed, in which case the sleeve 3 would make eight intermittent partial rotations in making a complete rotation, and if desired, more than one gap may be formed in the guides, or flanges, 41 and 41^a so that pressure may be released before the respective mandrels, or formers, have been carried a complete rotation.

What I claim is:

1. In apparatus for making paper bags, a former on which the bag is made, a presser foot pivotally connected to the former and adapted to press against a bag on the former, means for operating said presser foot, and associated elements indicating the action of the presser foot.

2. In apparatus for making paper bags, a former on which the bag is made, a presser foot pivotally connected to the former and adapted to press against a bag on the former, means for operating said presser foot, and comprising a toggle driver connected to the presser foot and having elements separating when the presser foot is in operating position.
- 10 3. In apparatus for making paper bags, a former on which the bag is made, a presser foot pivotally connected to the former and adapted to press against a bag on the former, means for operating said presser foot, and comprising a toggle driver connected to the presser foot and having a pair of coöperating members, spring means for pressing the same together, and an operating connection between one of said members and the presser foot to cause the separation of said members when the presser foot is in operative position.
- 15 4. In apparatus for making paper bags, a former on which the bag is made, a presser foot pivotally connected to the former and adapted to press against a bag on the former, means for operating said presser foot, said means comprising a pivoted toggle lever, a second toggle lever pivoted to the free end 20 of the pivot toggle lever, a link connecting the second toggle lever to the presser foot, and reciprocating jaws operatively engaging the first toggle lever to actuate the same, together with means for maintaining the presser foot in bag-engaging position for a predetermined period.
- 20 5. In apparatus for making paper bags, a former on which the bag is made, a presser foot pivotally connected to the former and adapted to press against a bag on the former, means for operating said presser foot, said means comprising a pivoted toggle lever, a second toggle lever pivoted to the free end 25 of the pivot toggle lever, a link connecting the second toggle lever to the presser foot, and reciprocating jaws operatively engaging the first toggle lever to actuate the same, together with a cam for operating said reciprocating jaws, and a fixed guide serving 30 to hold the toggle elements in stationary position for a predetermined period when the presser foot is in engagement with the bag on the former.
- 25 6. In apparatus for making paper bags, a former on which the bag is made, a presser foot pivotally connected to the former and adapted to press against a bag on the former, means for operating said presser foot, said means comprising a pivoted toggle lever, a second toggle lever pivoted to the free end 35 of the pivot toggle lever, a link connecting the second toggle lever to the presser foot, and reciprocating jaws operatively engaging the first toggle lever to actuate the same.
- 30 5. In apparatus for making paper bags, a former on which the bag is made, a presser foot pivotally connected to the former and adapted to press against a bag on the former, means for operating said presser foot, said means comprising a pivoted toggle lever, a second toggle lever pivoted to the free end 35 of the pivot toggle lever, a link connecting the second toggle lever to the presser foot, and reciprocating jaws operatively engaging the first toggle lever to actuate the same.
